Letters Patent No. 1350 Dated Decr 4th 1860

The Schedule referred to in these Letters Patent and making part of the same.

To all whom it may concern:

Be it known that I, Isaac De Zouche of the City of St. Louis, in the County of St. Louis, and State of Missouri have invented or produced a new and original design of a Cylinder Heating Stove, and I do hereby declare that the following is a full and exact description of the same, reference being had to the accompanying drawings, and to the letters of reference marked thereon, making part of the specification.

A represents a perspective view of my stove, the ornamentation of which is shown in the detail drawings B, and C. B, is the front plate, and C, the back plate. d, d, are scroll ornaments, each enclosing a shell. e, e, are the feet formed by a scroll above from which depends a piece of chain work, the lower part representing the foot of a lion. F, is a carved moulding, representing alternate circular and oblong beads separated by flat bands, one overlapping the other, at the intersections. G, G, is an ornamental shield, oval in form bearing the words "Bridge Beach & Co. St. Louis," with scroll work at the sides and
